CLAIM

The ornamental design for an inflatable swimming pool, as shown and described.

DESCRIPTION

FIG. 1 is a perspective view of a first embodiment of an inflatable swimming pool showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is an enlarged view of portion 10 shown in FIG. 1;

FIG. 11 is a perspective view of a second embodiment of the

inflatable swimming pool showing my new design;

FIG. 12 is another perspective view thereof;

FIG. 13 is another perspective view thereof;

FIG. 14 is a front elevational view thereof;

FIG. 15 is a rear elevational view thereof;

FIG. 16 is a left side elevational view thereof;

FIG. 17 is a right side elevational view thereof;

FIG. 18 is a top plan view thereof;

FIG. 19 is a bottom plan view thereof;

FIG. 20 is an enlarged view of portion 20 shown in FIG. 11;

FIG. 21 is a perspective view of a third embodiment of the

inflatable swimming pool showing my new design;

FIG. 22 is another perspective view thereof;

FIG. 23 is another perspective view thereof;

FIG. 24 is a front elevational view thereof;

FIG. 25 is a rear elevational view thereof;

FIG. 26 is a left side elevational view thereof;

FIG. 27 is a right side elevational view thereof;

FIG. 28 is a top plan view thereof;

FIG. 29 is a bottom plan view thereof; and,

FIG. 30 is an enlarged view of portion 30 shown in FIG. 21.
